DESIGN FOR A DRESS

Lee Friend and Emanuel S. Wieder, New York,
N. Y.

Application November 18, 1939, Serial No. 88,427

Term of patent 3½ years

To all whom it may concern:

Be it known that we, Lee Friend and Emanuel S. Wieder, citizens of the United States, and both residents of New York city, in the county and State of New York, have invented a new, original, and ornamental Design for a Dress, of which the following is a specification, reference being had to the accompanying drawing, forming a part thereof in which:

Fig. 1 is a front perspective view of a dress showing my new design.

Fig. 2 is a side view of Fig. 1, illustrating one sleeve of the dress raised.

Fig. 3 is a rear view of Fig. 1.

We claim:

The ornamental design for a dress, substantially as shown.

LEE FRIEND.
EMANUEL S. WIEDER.
